UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed February 24, 1925. Serial No. 11,183.

To all whom it may concern:

Be it known that I, HAROLD G. WARR, a citizen of the United States, residing at Park Ridge, in the county of Cook and State 5 of Illinois, have invented certain new and useful Improvements in Rail Anchors, of which the following is a specification.

My invention relates to improvements in rail anchors and has for its object to provide an improved one-piece anchor device 10 adapted to be distorted during its application to a rail, to effect a firm spring grip on the base flange of the rail.

A more specific object of the invention is to provide a one-piece rail anchor formed at one end with a jaw portion adapted to be moved into gripping engagement with the upper and lower surfaces of a rail base by a swinging movement of the anchor about an 15 axis extending longitudinally of the rail and formed at the other end with a portion which is flexed into gripping engagement with the opposite edge of the rail base, whereby the anchor device, by reason of its tendency to 20 return to the position from which it was sprung, exerts spring pressure vertically upon the upper and lower surfaces of the rail base at one side of the rail and exerts spring pressure transversely of the rail 25 against opposite edges of the rail base.

Another object of the invention is to provide an improved anchor device of the above character which is so formed as to provide a tie abutting portion adapted to bear against 30 one of the vertical faces of a cross tie at a substantial distance below the lower surface of a rail base and which is so formed as to be distorted to its rail gripping position by flexing one end of the device downwardly 35 and outwardly during the application of the anchor to a rail.

The invention has for further objects such other new and improved constructions relating to rail anchor devices, as will be hereinafter described and claimed for carrying out the above stated objects, and such other objects as may appear from a description of a preferred embodiment of my invention.

In the drawing:

Fig. 1 is a plan view of a rail base showing a rail anchor constructed in accordance with my invention, applied thereto, in operative

position to bear against a vertical face of a cross tie.

Fig. 2 is a view in cross section of a rail- 55 road rail, showing the manner in which my improved rail anchor is hooked over the opposite edges of the rail base.

Fig. 3 is a cross section of a rail base showing my improved anchor applied to its rail 60 base gripping position, and

Fig. 4 is a view in perspective of the rail anchor.

Referring to the drawing, 10 designates a railroad rail, supported on a cross tie 11, and 65 12 is my improved anchoring device adapted to grip the base portion 13 of the rail, and bear against the cross ties so as to resist longitudinal movement of the rail.

My improved anchor device is made preferably from a steel bar, one end of which is bent upon itself to form a hook-shaped jaw portion 14, adapted to grip the rail base 13 at one side of the rail, and the other end is bent to provide an upwardly and inwardly 70 projecting arm 15, adapted to engage the base flange at the opposite side of the rail.

The jaw portion 14 includes a part 16 which bears at its extremity against the upper surface of the rail base at a point remote from the adjacent edge of the base, a part 17 for engaging the vertical surface 18 of the base, and a part 19 provided with a flat bearing surface 20 adapted to bear against the bottom surface of the rail base 80 adjacent its lower corner. The part 16 of the jaw preferably extends at an angle to the inclined upper surface of the rail base, so as to confine its engagement with the rail base to a point intermediate the adjacent edge of 85 the base and the longitudinal center thereof.

The body portion of the bar is bent at an angle with respect to the part 19, so as to provide a downwardly extending portion 21, the extremity of which is bent to form the 95 arm 15, which extends upwardly and inwardly with respect to the edge 22 of the rail base. The lower portion of the arm 15 together with the downwardly extending body portion 21 of the anchor provides a 100 tie abutting portion which bears against a vertical face of the cross tie 11, at a substantial distance below the bottom surface of the rail base. The arm 15 is formed near

its upper end with a notch 23 adapted to fit over the edge of the rail base on the side opposite to that engaged by the jaw portion 14. The arm 15 is preferably formed so that the distance between the face 24 of the jaw and the face 25 of the notch 23 is normally less than the width of the rail base, when the anchor device is free of the rail, and so that it is necessary, when applying 10 the anchor to a rail, to flex the arm 15 outwardly with respect to the edge 22 of the rail base. This flexing action of the arm 15 is facilitated by the inclined inner surface 26 of the arm 15 which bears against 15 the edge of the rail so as to function as a cam, adapted, when the arm 15 is forced downwardly, to force the arm 15 outwardly with respect to the adjacent edge of the rail. 20 In applying the anchor to a rail, the arm 15 is first hooked over one edge of the rail base in the manner indicated in Fig. 2 of the drawing, and the jaw end is then raised until the lower edge of the part 16 clears 25 the upper edge of the base. In this position the anchor may be moved bodily to the right, so that the parts 16 and 19 of the jaw will embrace the upper and lower surfaces of the rail base. The extremity of the part 30 16 of the jaw and the flat bearing surface 20 of the part 19 are moved into gripping engagement with the upper and lower surfaces of the rail base by swinging the end of the anchor about an axis extending longitudinally of the rail base. This swinging movement is effected preferably by forcing the arm 15 downwardly until the notch 23 snaps over the edge 22 of the rail base. This downward movement of the arm 15 35 40 stresses the jaw portion of the anchor so as to exert vertical spring pressure on the upper and lower surfaces of the rail base. By reason of the engagement of the inclined face 26 of the arm 15 with the edge of the rail base, the arm is flexed outwardly with respect to the edge 22 of the rail base. When the arm snaps into its operative position, as shown in Fig. 3, the anchor device exerts a spring grip transversely of the rail against 45 50 55 opposite edges of the rail base. The tie abutting portion extends preferably at a substantial distance below the rail base and at a point beyond the edge of the base engaged by the arm 15, thereby providing a substantial bearing surface for bearing against the tie.

While I have described my invention in connection with a specific embodiment, it will be obvious that various changes in 60 structure might be made without departure from the spirit of the invention. It will therefore be understood that I contemplate all such modifications in structure as come within the scope of the appended claims.

65 I do not claim broadly herein the inven-

tion common to the device herein shown and to the device shown in my co-pending application, Serial No. 11,182 filed February 24, 1925, as the common invention is claimed in my said co-pending application. 70

I claim:

1. A rail anchor comprising a bar formed at one end with a jaw portion adapted to be moved into gripping engagement with the top and bottom surfaces of a rail base 75 at one side of the rail by a downward swinging movement of the other end of the bar, said last mentioned end being formed with a portion adapted to snap into engagement with the other edge of the rail base. 80

2. A rail anchor comprising a bar formed at one end with a jaw portion provided with parts for embracing the upper and lower surfaces of a rail base at one side of the rail and adapted to be moved into gripping engagement with said surfaces by a downward swinging movement of the other end of the bar, said last mentioned end being formed with a portion adapted to snap into engagement with the upper edge of the rail base. 90

3. A rail anchor comprising a bar formed at one end with a jaw portion adapted to be moved into gripping engagement with the upper and lower surfaces of a rail base at one side of the rail by a downward 95 swinging movement of the other end of the bar, said last mentioned end being formed with an arm which is flexed outwardly during the application of the device to a rail, and snapped into engagement with the edge 100 of the rail when the device is in its applied position.

4. A rail anchor comprising a member formed at one end with a jaw portion adapted to grip one surface of the rail base at a point adjacent one longitudinal edge of said base, and the oppositely disposed surface at a point intermediate said edge and the longitudinal center of the base, and formed at the other end with an arm adapted to be flexed 110 outwardly and downwardly into operative engagement with the edge of the rail base at the other side of the rail, the said jaw portion and said arm being so arranged with respect to each other that the jaw portion is moved into gripping engagement with the rail base by the downward movement of said arm. 115

5. A rail anchor comprising a member formed at one end with a jaw portion adapted to engage the bottom surface of the rail base at a point adjacent the edge of said base and the upper surface at a point intermediate the edge and the longitudinal center of the base, and formed at the other end with an arm adapted to be flexed downwardly and outwardly into operative engagement with the edge of the rail base at the other side of the rail, the said jaw portion and said arm being so arranged with 120 125 130

respect to each other, that the distortion of the anchor incident to downward movement of said arm effects a spring grip of the jaw portion on the upper and lower surface of 5 the rail base.

6. A rail anchor comprising a member formed at one end with a jaw portion adapted to engage the bottom surface of the rail base at a point adjacent one edge of said 10 base and the upper surface of the rail base at a point intermediate the edge and the longitudinal center of the base, and formed at the other end with an arm adapted to be flexed outwardly and downwardly into 15 operative engagement with the edge of the rail base at the other side of the rail, the said jaw portion and said arm being so arranged with respect to each other that movement of said arm downwardly to its operative position tensions said jaw portion so as to exert a spring grip on the upper and lower surfaces of the rail base.

7. A rail anchor comprising a member formed at one end with a jaw portion adapted to engage the bottom surface of the rail base at a point adjacent one edge of said base, and the upper surface at a point intermediate the edge and the longitudinal center of the base, and formed at the other end with an arm adapted to be flexed outwardly and downwardly into operative engagement with the edge of the rail base at the other side of the rail, the said jaw portion and said arm being so arranged with 30 respect to each other that movement of said arm downwardly to its operative position tensions said jaw portion, so as to exert a spring grip on the upper and lower surfaces of the rail base, and that the outward movement of the arm so tensions the anchor as 35 to exert a spring grip on the opposite edges of the rail base transversely of the rail.

8. A rail anchor comprising a member formed at one end with a jaw portion adapted to grip the upper and lower surfaces of 45 a base of a rail at one side of the rail and formed at the other end with an arm for engaging the opposite edge of the rail base; said arm and jaw portion being so disposed with relation to each other, that said arm is 50 first hooked over one edge of the rail base to permit the jaw portion to be hooked over the opposite edge of the rail base.

9. A rail anchor comprising a member formed at one end with a jaw portion adapted to engage with the base of a rail at one side of the rail and formed at the other end with an arm for engaging the opposite edge of the rail base; said arm and jaw portion being so disposed with relation to each other 60 that said arm is first hooked over one edge of the rail base to permit the jaw portion to be hooked over the opposite edge of said base and is forced downward to move said jaw portion into normal gripping engagement with the upper and lower surfaces of 65 said rail base.

10. A rail anchor comprising a member formed at one end with a jaw portion adapted to engage with the base of the rail at one 70 side of the rail, and formed at the other end with an arm for engaging the opposite edge of the rail base; said arm and jaw portion being so disposed with relation to each other that the arm is first hooked over one edge 75 of the rail base to permit the jaw portion to be hooked over the opposite edge of the rail base, and is forced downwardly and flexed outwardly to effect a vertical grip of said jaw portion on the upper and lower surfaces 80 of the rail base and to exert a spring grip transversely of the rail against opposite edges of the rail base.

HAROLD G. WARR.
